UNITED STATES PATENT OFFICE.

ALEXANDER HOFFMANN, OF BERLIN-REINICKENDORF, AND BERNHARD BOMBORN,
OF BERLIN, GERMANY; SAID HOFFMANN ASSIGNOR TO SAID BOMBORN.

CRAE.

Application filed June 29, 1920. Serial No. 392,826.

To all whom it may concern:

Be it known that we, ALEXANDER HOFFMANN, a citizen of Russia, and BERNHARD BOMBORN, a citizen of the Republic of Germany, 5 residing at Berlin-Reinickendorf, Germany, and Berlin, Germany, respectively, have invented certain new and useful Improvements in Crabs, of which the following is a specification.

10 My invention refers to lifting devices and more especially to a device for hoisting and transporting goods in which a single driving member (e. g. an electromotor) works the hoisting and the transport. It is an object of my invention to insert a planet gear between the driving member (electromotor) and either the hoist gear or the transport gear in such wise that by alternately tightening and loosening (coupling and uncoupling) parts of the intermediate gear, the movement of the motor is transferred either to the hoist gear or to the transport gear. Apart from some essential constructions of the gear the mode of steering the electromotor forms a further prominent feature of my invention.

15 In the drawings affixed to this specification and forming part thereof different modifications of this invention are shown by way of example.

In the drawings

Fig. 1 is a longitudinal section of the device.

20 Fig. 2 is a section following the line A—B in Fig. 1, as viewed from the right,

Fig. 3 a vertical section of Fig. 2 in the plane of shaft 28 showing the coupling levers,

25 Fig. 4 is a side view of another modification.

Fig. 5 a section following line C—D in Figs. 4 and 6,

Fig. 6 a longitudinal section,

30 Fig. 7 a section following line E—F in Fig. 6 as viewed from the right,

Fig. 8 a section following line I—K in Fig. 6 as viewed from the right,

35 Fig. 9 a section following line G—H in Fig. 6 as viewed from the right,

Fig. 10 a longitudinal section of a third modification with two pairs of planet wheels,

40 Fig. 11 the gear as shown in Fig. 12 in longitudinal section, applied to a swivelling crane;

Figs. 13 and 14 show two further modifications.

Referring to Figs. 1 to 3 of the drawings, 55 1 is the I-beam, 2 are the wheels that run on its bottom flange. Shaft 21 of electromotor 4 projects into the chest 11 capsuling the gear and bears a driver 6. This latter meshes with a tooth-wheel 7 whose centre shaft 8 rotates in a crank or disk 16. The driver 9 of this shaft 8 is engaged with a tooth-wheel 10, which is connected with rope-drum 15' or a chain-wheel by means of the wheels 13 and 14.

The disk 16 has an external toothed rim 17 which can be made to mesh with the tooth-wheels 18, 19 and 20 and so act upon the wheels 2.

50 Chest 11 supports a shaft 28 which has two eccentrical cam discs 25, 26 displaced relatively to one another and which can be moved backwards and forwards by a rope 75 or commanding pulley 27. These cams press against the arms of double levers 23, 24, whose opposite ends are cogged and fit into the toothed rims of the rotating crank 16 or the tooth-wheel 10. One or several springs 80 29 endeavor to throw the gear in by their pressure. The eccentrics 25, 26 are displaced relatively to each other so that lever 23 engages the tooth-wheel 17 and couples it when 24 is uncoupled, and vice versa (Fig. 85 2 shows the latter position.)

Supposing the command pulley 27 to be turned so that lever 23 couples the wheel 17 and that lever 24 does not touch wheel 10, if now the rotor is set in motion, the latter is transferred by tooth-wheels 6, 7, 9, 10, 13, 14 to the rope-drum 15'. In this case a highly efficient normal gear is attained. If on the other hand the coupling is reversed by moving the command pulley 95 27, i. e. if tooth-wheel 10 is coupled then the motor shaft 21 turns the driver 6 and tooth-wheel 7, whose driver 9 fixed upon shaft 8 revolves around wheel 10 as a planet wheel; crank 16 revolves in a like manner 100 and its movement is transferred to the wheels 2 by means of the tooth-wheels 18, 19, 20. To ensure a good balancing of forces the wheels 7, 9 can be arranged in pairs opposed to each other; the centre hole for the other shaft is shown at the bottom of crank 16. 3 and 5 signify a brake and brake disk.

separated and the rope-drum is arranged between them. Here the motion is transferred to the transport wheels 2 from the rotating crank 16 by the wheels 89, 90, 91. In Fig. 13 5 the hoisting member consists of a chain-wheel 15, in Fig. 14 of a rope-drum 15'. Importance must be attached to the fact that the electromotor 4 and its commanding machinery as well as the gear inside the gear- 10 chest 11 remain exactly the same. Solely the supporting frame 12 in Fig. 14 must be longer than in Fig. 13; equally must the motor shaft 21 be elongated (e. g. by inserting an adapting or coupling piece) and the 15 chain-wheel 15 of Fig. 13 must be exchanged for a driver 92 in Fig. 14, which meshes with a toothed rim (in this case an inside rim 93) of drum 15'. By inserting this intermediate gear 92, 93 an identical hoisting 20 speed of drum 15' and of chain-wheel 15 is obtained. Thus the motor power is exploited to the same degree for chain and rope drive and identical castings for the entire gear are obtained for chain and rope drive, 25 whereby the manufacture of the individual types is made less expensive.

The overhead crabs can equally be fitted to be used for rope conveyors and for central command.

30 We wish it to be understood, that we do not desire to be limited to the exact details of construction shown and described, for obvious modifications will occur to a person skilled in the art.

35 We claim:

1. A load lifting and traversing device comprising in combination, a motor, a winch, a traversing wheel, a planet wheel gear, comprising a planet wheel carrier and a planet wheel, inserted between said motor and said winch and traversing wheel, a driving wheel for said planet gear disposed coaxially with said planet gear and means for separately locking said planet wheel carrier and said 45 winch, respectively.

2. A load lifting and traversing device comprising in combination, a motor, a winch, a traversing wheel, a planet wheel gear, comprising a planet wheel carrier and a planet wheel, inserted between said motor and said winch and traversing wheel, a tooth gear meshing with said winch, a driving wheel for said planet gear disposed co-axially with said planet gear, said planet wheel meshing with said tooth gear and means for separately locking said planet wheel carrier and said tooth gear, respectively.

3. A load lifting and traversing device comprising in combination, a motor, and a motor shaft, a winch, a traversing wheel, 60 a planet wheel gear, comprising a planet wheel carrier and a planet wheel, inserted between said motor and said winch and traversing wheel, a tooth gear meshing with said winch, a driving wheel for said planet 65 gear disposed coaxially with said planet gear, on said motor shaft, said planet wheel meshing with said tooth gear and means for separately locking said planet wheel carrier and said tooth gear, respectively. 70

4. A load lifting and traversing device comprising in combination, a motor, a winch, a traversing wheel, a planet wheel gear, comprising a planet wheel carrier and a pair of planet wheels arranged coaxially on said carrier, inserted between said motor and said winch and traversing wheel, a tooth gear meshing with said winch, a driving wheel for said planet gear disposed coaxially with said planet gear, one of said planet wheels 75 meshing with said tooth gear, the other with said driving wheel and means for separately locking said planet wheel carrier and said tooth gear, respectively.

5. A load lifting and traversing device 85 comprising in combination, a motor, a winch, a traversing wheel, a planet wheel gear, comprising a planet wheel carrier and a planet wheel, inserted between said motor and said winch and traversing wheel, an internally 90 toothed wheel meshing with said winch and comprising an internally toothed wheel, a driving wheel for said planet gear disposed coaxially with said planet gear, said planet wheel meshing with said internally toothed 95 wheel and means for separately locking said planet wheel carrier and said internally toothed wheel, respectively.

6. A load lifting and traversing device comprising in combination, a motor, a winch, 100 a traversing wheel, a planet wheel gear, comprising a planet wheel carrier and a planet wheel inserted between said motor and said winch and traversing wheel, a driving wheel for said planet gear disposed coaxially with 105 said planet gear and spring-controlled cogged levers for separately locking said planet wheel carrier and said winch, respectively, and means for alternately traversing one of the other levers in. 110

In testimony whereof we affix our signatures.

ALEXANDER HOFFMANN.
BERNHARD BOMBORN.
